UNITED STATES PATENT OFFICE.

ABRAM COX MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

COMBINED GAS AND COAL HEATING-STOVE.

No. 926,585.

Specification of Letters Patent.

Patented June 29, 1909.

Application filed November 29, 1905. Serial No. 289,585.

To all whom it may concern:

Be it known that I, ABRAM COX MOTT, Jr., a citizen of the United States, residing in Philadelphia, Pennsylvania, have invented 5 certain Improvements in Combined Gas and Coal Heating-Stoves, of which the following is a specification.

The object of my invention is to make a heating stove so that either gas or coal can be 10 used as fuel. This object I attain in the following manner, reference being had to the accompanying drawings, in which:—

Figure 1, is a vertical sectional view of my improved stove partly in elevation showing 15 the gas apparatus in position; Fig. 2, is a vertical sectional view on the line 2—2, Fig. 1, partly in elevation; Fig. 3, is a sectional view of a portion of the stove arranged to burn coal as the fuel; and Fig. 4, is a perspective 20 view of the gas burner.

A is the body of the heating stove of the ordinary shape. This body is mounted on a base a provided with suitable legs a'.

B is the ash pit.

25 C is the fire pot having the fingers c in the present instance.

D is the grate having a central opening d and a slide D' is mounted in ways so as to open or close said opening. The slide is provided with a suitable handle d' projecting 30 through an opening in the base of the stove.

E is a central chamber or hopper for containing the coal, when coal is used as the fuel.

35 a² is the opening for the escape of the products of combustion.

At the back of the stove are two flues a³ and in the base is a flue a⁴ and the products of combustion can be either directed by the 40 damper b to the outlet a² directly from the combustion chamber, or indirectly through the flues a³, a⁴ and then to the outlet. This is an ordinary type of heating stove.

In many cases it is more convenient to use 45 gas as a fuel rather than coal and especially where the heat is not required at all times, such as in the fall and spring of the year. I have, therefore, designed a stove which can be used either for gas or coal, as desired.

50 The gas apparatus can be readily removed without dismantling the stove so that it can be shifted in a very few minutes from one style of heater to another.

At each side of the stove in the present 55 instance are fenders b' which are usually

intended only for ornamental purposes, but I utilize one of these fenders to carry the gas supply pipe I, which has a branch i provided with a valve i', and this branch enters an opening in the casting I' secured to the base 60 section of the stove in line with the ash pit.

N is a gas burner circular in form in the present instance, and is provided with a supply pipe n having a branch n' turned at right angles to the pipe n, so that when it is in 65 position it is in line with the gas pipe i and its end is so shaped as to rest in the casting I'. The gas burner N is detachably mounted in the fire pot above the grate, the legs n² resting upon the grate and the supply pipe n 70 extends through the central opening d in the grate, the slide D having been moved to one side as indicated in Fig. 1, the burner being mounted in the stove without dismantling any portion of the grate or fire pot. 75

I preferably mount a cage M in the fire pot above the burner to hold composition blocks representing coal; the burning gas will pass through the body of material and heat it to incandescence, making it appear as if coal 80 was the fuel.

In order to deflect the products of combustion I preferably mount a shield K above the fire pot at the back of the stove directly in front of the damper b, the lower end of the 85 shield resting on the fire pot and the upper end resting against the walls of the hopper E, so that while the damper b is open, as indicated in Fig. 2, the products of combustion will not pass directly to the flue but will 90 be deflected by the shield.

When it is desired to place the gas burner in position the fire door e is first opened and the depending portion of the hopper E is pushed up, the slide D' is moved out and the 95 burner is passed through the fire door into the fire pot and turned so that the pipe n will pass through the opening in the grate, after which it is turned so that it will pass into the casting I' in direct line with the gas pipe. 100 The cage M is then placed in position and the deflector K is also placed in position, after which the hopper is lowered and the stove is then ready to burn gas as a fuel.

I claim:

The combination in a heating stove, of a body portion, having a fire pot and ash pit, a grate with an open center separating the fire pot from the ash pit, a slide for closing said opening, the side wall of the ash pit hav- 110

ing an opening therein, a gas pipe having an extension terminating at the opening, a detachable circular burner having a right angled pipe depending from its center, the body of the burner being supported by the grate and the pipe extending through the opening in the grate and alining with the opening in the side wall of the ash pit.

In testimony whereof, I have signed my name to this specification, in the presence 10 of two subscribing witnesses.

ABRAM COX MOTT, JR.
